UNITED STATES PATENT OFFICE

2,656,084

JAR-HANDLING EQUIPMENT FOR CAPPING MACHINES

Arthur H. Filander, Baltimore, Md., assignor to
 Franklin Balmar Corporation, Baltimore, Md.,
 a corporation of Maryland

Application January 2, 1952, Serial No. 264,495

1 Claim. (Cl. 226—88)

1

This invention relates to jar-handling equipment for capping machines, and more particularly to feeding, conveying and guiding mechanism for the handling of the jars or bottles to be capped, and to the driving system for the conveyor mechanism, as well as to means of adjustment whereby the equipment is adapted to feed, convey and guide screw-cap types of bottles or jars of a variety of shapes, sizes, heights, diameters and weights.

A major object of the invention is to ensure that, regardless of the variations in the jars handled, there will be a rapid, accurate, reliable delivery of the jars, serially, to the capping station, and discharge thereof from said station, in an assured coordinated relationship with the operations of the jar grippers, the capping unit and other elements of the machine, and with a minimum of interruption due to jar breakage or to any other cause.

More specifically, the invention contemplates the accomplishment of the foregoing and other objects by the provision of a reciprocating-type of conveyor, positively coordinated with the jar-gripping and cap-setting units; and desirably the accomplishment of this by the employment of novel driving connections for the conveyor actuated from the same driving motor which operates one or more of the mentioned elements of the machine.

Still further, the invention contemplates accomplishing the foregoing with the further cooperation of one or more of the following features: replaceable and/or adjustable elements in the conveyor and its drive; adjustable feed means associated with the conveyor; jar guiding means associated with the reciprocating conveyor and adjustable both vertically and horizontally, and in the preferred form by a pivotal and sliding adjustment mechanism capable of accomplishing both vertical and horizontal adjustments, and adapted also to adjust a brake.

How the foregoing, together with such other objects and advantages as are incident to or inherent in the invention, are attained, will be evident, to those skilled in the art, from the following description when taken with the accompanying drawings, wherein:

Figure 1 is a front elevational view of an automatic machine for screwing caps upon jars, utilizing the feeding, conveying, guiding and other features of the present invention, the view being partly in section substantially on the line 1—1 of Figure 2;

Figure 2 is a sectional elevational view of the

2

machine taken substantially on the line 2—2 of Figure 1;

Figure 3 is a plan section of the machine taken substantially on the line 3—3 of Figure 1;

5 Figure 4 is a detailed plan view of a carriage for supporting the driving unit of the machine;

Figure 5 is a fragmentary plan section taken on the line 5—5 of Figure 2;

10 Figure 6 is an enlarged fragmentary plan section taken on the line 6—6 of Figure 2;

Figure 7 is a vertical sectional view of a capping unit employed;

15 Figure 8 is a sectional elevational view showing the position of the parts with the crank wheel rotated 180° from the position of Figure 2;

Figure 9 is a fragmentary face view of the crank wheel and associated parts, some of them being in section;

20 Figure 10 is an enlarged plan section taken on the line 10—10 of Figure 1 with the guide bar omitted in order to show clearly the brake mechanism employed in the machine;

Figure 11 is a face view of Figure 10;

25 Figure 12 is a fragmentary detail view of the brake and associated guide bar; and

Figure 13 shows the parts of Figure 12 in a different position of adjustment.

A typical machine, in association with which my invention has been applied, comprises, in general, suitable frame structure F having horizontal framing members 10, 10 and 11, 11, and vertical framing members 12 and 13; a driving unit D mounted on a carriage 14; a capping unit or cap setter C; jar receiving and guiding rails G and G' for the jars J; clamping mechanism M for arresting and gripping the jars so as to stop and hold them at a capping station during the capping or cap setting operation; and a braking mechanism B at the capping station, for retarding the jars, particularly when the machine is operating at very high speeds. I have applied to such machine my novel conveyor system R, with its reciprocating driving system as hereinafter described, with associated feed mechanism (including adjustable and replaceable guide members indicated at T and at 35), and a special adjusting system (best seen in detail in Figures 10 to 13) for the guides G and G'. It should be understood that various features of the machine, such as the driving unit B, capping unit C, guide rails per se, clamping mechanism M, braking mechanism B, and certain associated parts, although illustrated and described herein because of their association with features of my invention, do not in themselves constitute elements of

30

35

40

45

50

my invention (certain of the same being claimed in application of Edward Demski Serial No. 264,493, entitled Automatic Machinery for Screwing Caps Upon Jars, filed January 2, 1952, and assigned to the assignee of the present invention). Referring now to the construction of the machine in more detail:

The drive unit D comprises a motor 15, a worm 16 mounted on one end of the motor shaft, a worm wheel 17 mounted on the drive shaft 18 of the capping unit C, a gear 19 mounted on the other end of the motor shaft, a meshing gear 20 mounted on the shaft 21 of a drive pulley 22, and a crank wheel 23 driven from the drive pulley by a belt 24.

The crank wheel 23 (as best seen in Figs. 1, 2 and 9) is provided with a crank pin 25 on which the head 26 of a rod 27 is mounted by means of a bearing 26a. The rod 27 is pivotally anchored to the frame of the machine by means of a trunnion 28 mounted in bearings 29, the rod 27 being adjustably secured to the member 28 by a set screw 30.

As thus far described it will be seen that when the crank wheel 23 is rotated the crank pin causes the carriage 14, carrying the drive unit D, to move up and down due to the anchorage of the rod 27.

The carriage is mounted for this up and down movement by means of wheels 31 riding on rails 32 carried by the upright frame members 12. As best seen in Figures 1, 2 and 4, the carriage 14 has a base 14a on which the motor 15 with the gear case 16a and the bearing 23a for the crank wheel 23 are mounted, and four upwardly extending side arms 14b each of which carries a pair of the wheels 31, the wheels being spaced widely apart to counteract any tilting action due to the overhang of the crank drive and the capping unit as viewed in Figure 2.

The capping unit is secured to the drive shaft 18 by means of a key 33 and set screw 34 (see Figure 7) and therefore the capping unit is brought into engagement and disengagement with the jar caps as the carriage is moved up and down.

Jars J, with their caps or lids hand-applied thereon are fed to the machine by any known form of feeding conveyors arranged for either parallel or right angle feed to the machine. Where the initial feed conveyor delivers in a direction parallel to the reciprocating conveyor mechanism R of my invention, I provide a curved lead-in or feed rail T, and a cooperating adjustable feed plate or end guide 35; and where a right-angled initial feed conveyor is used, I may employ the same plate 35 and the adjustable straight rail T' (as best seen in Fig. 3). The guide 35 is slotted (as shown) for adjustment to suit the particular diameter of jar being handled, which, in this instance, is illustrated as being of the quart Mason jar size. The lead-in rail T (or T') is also adjustable as by means of a screw and slot connection 35a to suit the diameter of jar being handled.

In this connection it is pointed out that it is contemplated that jars of various heights and diameters will be handled in the machine, for example, jars ranging from $2\frac{1}{4}$ inches to $4\frac{1}{8}$ inches in diameter and from $3\frac{1}{2}$ inches to $7\frac{3}{4}$ inches in height. To enable the handling of the large variety of jar sizes falling in the above range, the feed guide 35, the lead-in rail T, the clamping mechanism M, the guide rails G and G', the brake B, the capping unit C and the conveyor unit R are made adjustable in a simple manner, as will appear hereinafter.

As seen in Figures 1 and 3, the jars are guided

by the lead-in rails T or T', as the case may be, onto the horizontal frame members 10 of the machine and are then fed along these members in step-by-step movement by the reciprocating conveyor R, the jars being guided against lateral displacement by the guide rails G and G'.

Although horizontally adjustable guide rails are not per se my invention, I provide that the guide rails G and G' are mounted for up and down adjustment in accordance with the height of jar being capped as well as for adjustment toward and away from each other in accordance with the diameter of jar being capped. Rotatably adjustable mounting studs 36 are provided for the guide rails, and (as seen in Figs. 10 to 13), the mounting studs are adapted to be secured in various adjusted positions by means of screws 37. The mounting studs for the guide rail G are secured to the frame members 12 and the mounting studs 20 for the guide rail G' are secured in brackets 38 carried by the front frame member 10.

In Figure 12 the guide rail G is shown adjusted for one height of jar and in Figure 13 it is shown adjusted to a higher position for a taller jar. In order to properly guide jars of different diameter the guide rails are adjustably mounted in the studs 36 for in and out movement by means of rods 39 and set screws 40.

The height adjustment of the rail is of especial importance in preventing tipping, spilling or dislodgment of jars, especially when the machine is operated at very high speeds, since differences in height of jar usually involve differences in the center of gravity location, and it is desirable that the jars be laterally supported at a level not too far removed from the center of gravity of the jar.

The reciprocating conveyor R comprises conveyor bars 41 having wheels 42 riding on rails 43 secured to the horizontal frame members 10; gravity loaded pusher pins or fingers 44 for engaging and pushing the jars along the rail members 10 when the conveyor bar 41 is in its forward travel, i. e., in its travel to the left as viewed in Figures 1 and 3; and a bell crank lever having its arms 45, 45 connected by shaft 45a for imparting reciprocatory motion to the conveyor bars 41 and having connection therewith by means of an adjustable link 46 and bracket 47. The pusher pins 44 are replaceably screwed into the counterweights 49 whereby pins of different lengths may be employed to suit the particular size jars being conveyed. The counterweights are pivotally carried by the conveyor bars by means of pivot pins 48 fitting holes in the conveyor bars spaced therealong a distance somewhat greater than the diameter of the largest size jar to be handled in the machine. In the backward travel of the conveyor bars the pusher pins 44 pivot downwardly and pass under the jars, which remain stationary, and as the bars approach the end of their backward stroke the pins swing up under influence of counterweights 49. The backward stroke continues until the pins assume a position clear of the jars a distance indicated at 44a in Figure 1. This clearance provides a delaying action before the pins advance the jars on the forward stroke of the conveyor to enable the capping unit C to be raised free of the jar just capped in the backward stroke of the conveyor.

As seen in Figures 1 to 3, and 5 and 6, the clamping mechanism M for gripping the jars when they are being capped comprises clamp arms 50 hinged at 51 to adjustable hinge lugs 52 mounted on a turnbuckle 53 carried by lugs 54 secured to the frame members 11; pads 55

for gripping the jars; angular plates 56 secured to the clamp arms at their upper portions to which the pads are secured; and leverage, indicated as a whole by the reference letter L, for operating the clamps to be fully described hereinafter.

As best seen in Figure 3, the angular plates are in the form of a flat V, of about 120° included angle; and the double V formed by the two clamps acts to center the jar as it is being gripped. The clamp pads 55 are preferably constructed of a rubber compound and their gripping surfaces are preferably provided with circular grooves 55a (see Figure 1) to give them an effective grip.

The pads 55 are adjustable by means of screws 55b to aid in properly adjusting the mechanism for centering jars of different diameters under the capping head and to give an equal grip at each pad. Final grip adjustment is accomplished by means of the turnbuckle 53.

The capping unit or cap setter C which is secured to the drive shaft 18 by means of the key 33 and set screw 34 above mentioned comprises a driving sleeve 58, a friction body member 59 fitting the driving sleeve and retained by a pin and slot connection 60; friction inserts 61, preferably of fibre, carried by the member 59 and having a tapered bore 62 and keyways 63; a tapered driving member 64 fitting the tapered bore 62 and having keys 65 fitting the keyways 63; a torque adjusting nut 66 screwed onto the body member 59 and engaging the driving member 64; and adapter member 67 secured to the driving member 64; and a capping head 68 secured on the adapter member and having an insert 69, preferably of rubber, for gripping the jar lid to be tightened.

It is pointed out that since the driving member 64 has tapered engagement with the friction inserts 61 the frictional torque therebetween can be adjusted by tightening or loosening the adjusting nut 66.

In order to compensate for slight variation in jar heights and to provide a cushioned contact between the capping unit and the jar when the unit is brought into capping position, a cushioning spring 70 is provided between the driving sleeve 58 and the body member 59.

Reverting now to the conveyor unit R, reciprocatory movement is imparted thereto from the driving unit D (as seen in Figures 2, 3 and 8) by means of a downwardly extending drive rod 71 secured to the carriage 14 at 72 and having a bracket 73 adjustably secured thereto by means of a locking screw 73a. The bracket 73 has a horizontal arm 74 secured thereto which is connected to the lower arm of the bell crank lever 45, 45 by means of an adjusting link 75 (see Fig. 1). Thus when the carriage 14 is moved up, under the crank action of the crank wheel drive, the jars are moved a fixed distance along the frame members 10 by the conveyor fingers and a jar is brought into capping position under the capping unit C. Since the capping unit is also supported from the carriage 14 it will move upwardly during this forward movement of the conveyor. On the downward movement of the carriage the jars remain stationary and the conveyor moves in its backward stroke, i. e. to the right as viewed in Figure 1, and the capping unit moves down into capping position to tighten or set the cap. Thus by my particular conveyor and the reciprocating drive system therefor, coupled with the same drive unit which actuates the grippers and the turning and reciprocation of

the capping unit, I secure an absolutely certain coordination of the jar-handling mechanism with the operation of the various other elements of the machine.

5 In order to ensure proper positioning of the jar to be capped under the capping head, pressure brake mechanism B is provided at the capping station which acts to pressure hold the jar in the exact position of alignment with the capping head to which it was advanced by the conveyor. This prevents the jar from riding past its correct capping position as could be the case in the absence of such means, if the machine be operated at such a high speed as to so impel the jars.

Referring particularly to Figures 10 to 13 inclusive, the brake mechanism comprises a brake or pressure bar 103 having rearwardly extending guide rods 104 slidably fitting the holes in brackets 105 which are adjustably secured on the rods 39 of the guide rail G. The brake bar 103 is urged forwardly, i. e., in a direction toward the jars by means of pressure springs 106 surrounding the rods 104. Adjusting nuts 107 are provided for adjusting the tension of the springs 106.

As a jar approaches its capping position it engages the brake shoe portion 108 of the brake bar and it is pressure held between the brake bar and the guide rail G' thus preventing unintentional movement of the jar past its capping position. The brake bar can be adjusted inwardly and outwardly on the rods 39 and locked in adjusted position by the set screws 109.

Reverting now to the operation of the clamping mechanism M and referring particularly to Figures 1, 2, 6 and 8, a downwardly extending operating rod 76 is secured to the bracket 73 of the drive rod 71, as by means of a pin 76a, so as to reciprocate up and down therewith. This operating rod 76 is connected at its lower end to a pair of pull bars 77, 77 of the leverage L.

The operating rod 76 is guided in a tubular bearing member 81 rigidly attached to the machine frame as by means of welds indicated at 82. The bearing member 81 has a bearing sleeve 83 for the operating rod. A sleeve 80 extending downwardly from the bearing member 81 surrounds the operating rod 76 and houses a cushioning spring 78 seating at its lower end in a bottom cup 79 for the sleeve 80 and being engaged at its upper end by a collar 84 secured on the operating rod.

As seen in Figures 1, 2, 6 and 8, the upper ends of the pull bars 77, 77 are connected to one end of levers 85, 85 pivoted at 86 to the frame of the machine and connected at their other ends to links 87, 87 which in turn are connected to yokes 88, 88 connected to the clamp arms 50, 50 at 89, 89. This linkage is guided centrally by a guide member 90 secured to the machine frame having a slot 91 for a guide roller 92 mounted on the connecting pin 93 of the links 87 and yokes 88.

In operation as the drive rod 71 and connected operating rod 76 move downwardly, the clamp arms 50, 50 move inwardly to effect gripping of the jar, and as they move upwardly the arms 50 move outwardly away from the jar to release the grip (as seen in Fig. 8), and since the capping unit engages the jar in the downward movement of the drive rod the jar will be gripped while the cap is being tightened or set.

A complete cycle of operation of the machine, starting from the position shown in Figures 1 and 2 in which the capping head has just completed setting the cap, is as follows. First the con-

head. Conveyor adjustment may also be made by adjusting the rod 101 of the adjusting link 15.

A further adjustment desirably to be made with change of jar diameters is the position of the feed guide 35 which is accomplished by means of the screw and slot connections 102 shown in Figure 3. This guide 35 is moved in a direction toward the capping head for jars of smaller diameter. Also the lead-in rail T or T' is adjusted inwardly for the smaller jars.

In addition to the clamp arm adjustment above referred to, it may be desirable to provide several sizes of clamps. Also, in order to take care of a variety of cap sizes, capping heads 68 of various sizes may be employed.

It will now be apparent to those skilled in the art how I accomplish the feed, guidance, conveyance and discharge of the bottles or jars, in a reliable manner, closely coordinated with the other operations of the machine. Regardless of variations in weight, center of gravity, diameter, height and shape of jars or bottles, my conveyor mechanism with its drive system and its associated adjustable feed and guide mechanism will meet all the requirements imposed upon it.

I claim:

In a capping machine for setting loosely-applied caps of screw-type jars; a capping unit; a conveyor for feeding jars to a capping station relative to said capping unit; a carriage on which said capping unit is mounted; a support for mounting said carriage for up and down reciprocation to bring said capping unit into and out of engagement with a jar cap; clamping means for holding a jar on which the cap is to be set against rotation while said cap is being set; a motor mounted on said carriage; and driving connections between said motor and the carriage, the capping unit, the conveyor and the clamping means, said driving connections including a rotating crank and a pivotally anchored adjustable rod connected to said crank whereby up and down reciprocatory movement is imparted to the carriage, a drive rod secured to the carriage, a bracket adjustably secured on said drive rod, linkage and leverage connected between said bracket and the conveyor to impart reciprocatory movement of the drive rod to the conveyor, and linkage and leverage connected between said bracket and the clamping means to impart reciprocatory movement of the drive rod to the clamping means.

ARTHUR H. FILANDER.

veyor moves in its forward stroke and simultaneously the capping head moves upwardly away from the jar and the clamps release their grip on the jar, it being noted that the jars are not advanced until the conveyor has traveled through the distance 44a to enable the capping head 68 to raise clear of the jar before jar movement occurs. When the conveyor reaches the end of its forward stroke the next jar to be capped will be in alignment with the capping head and so held by the brake shoe 103. Next the conveyor moves in its backward stroke and simultaneously the capping head moves downwardly to engage and set the cap and the clamps move to grip the jar. This cycle is repeated as jars are advanced step-by-step to capping position. The finished capped jars are moved along the frame members 10 to a point of discharge.

As has been pointed out above, it is contemplated to employ the machine for capping jars of various diameters and heights, and to accomplish this, adjustments must be made when changing from one size of jar to another.

Assuming now that the machine is to be changed from capping jars of the large size illustrated in the drawings to capping jars of smaller height and diameter, the first step is to rotate the pulley 23 to bring the hole 94 provided in the operating rod 16 (Fig. 8) into registry with the hole 95 provided in the fixed bearing member 81 and to insert a holding pin in the registering holes. It will be seen from Figure 2 that when these holes are in registry the crank pin 25 is in its up position.

After insertion of the holding pin, the shaft 96a of the pinion 96 (which pinion engages the rack 97 of the drive rod 71) is held by a suitable wrench against rotation while the set screw 30 of the rod 27 is loosened and the locking screw 73a is unlocked by handle 73b to release the bracket 73. With these screws loosened, the carriage 14 is lowered by rotating the pinion 96 until the capping head 68 engages the cap of the smaller size jar. Next the screw 30 is tightened to lock the rod 27 in adjusted position and the screw 73a is tightened to secure the bracket 73 to the drive rod 71 and the holding pin is removed from apertures 94, 95. After the capping head has been brought into engagement with the jar cap in this manner, further adjustment of cap contact, if necessary, can be made by means of the adjusting nut 68a (Figure 7).

Next the clamp arms 50 are adjusted into engagement with the jar by turning the turnbuckle 53. Further adjustment of the clamp arms may be made by adjusting the nuts 77a and 77b on the screw end 77c of the rod 76 to move the connector bar 77d of the puller bar 77, 71 up or down. The guide rails G and G' are adjusted to suit the size of the jar in the manner above described.

If the diameter of the jar is such as to require a shorter stroke of the conveyor this is accomplished by positioning the yoke 98 of the link 46 in one of the lower holes 99 of the bell crank lever 45. The position of the conveyor bar 41 may be adjusted to suit the jar by means of the screw 100 of the link 46. This adjustment enables the jar to be exactly aligned with the capping
